UNITED STATES PATENT OFFICE

163,206

COMBINED FRAME AND SCREEN FOR TELEVISION OR PICTURE PROJECTION

Edward C. Klotz, Jr., Brookfield Township, Wis., assignor to Picture Recording Company, Oconomowoc, Wis., a corporation

Application April 1, 1950, Serial No. 8,910

Term of patent 7 years

(Cl. D56—4)

To all whom it may concern:

Be it known that I, Edward C. Klotz, Jr., a citizen of the United States, residing at Brookfield Township, State of Wisconsin, have invented a new, original, and ornamental Design for Combined Frame and Screen for Television or Picture Projection, of which the following is a specification, reference being had to the accompanying drawing, forming a part hereof.

The figure is a perspective view of the combined frame and screen for television or picture projection, showing my new design, the other sides thereof being plain. The dotted line disclosure is for illustrative purposes only.

I claim:

The ornamental design for a combined frame and screen for television or picture projection, as shown and described.

EDWARD C. KLOTZ, JR.
